UNITED STATES PATENT OFFICE.

PEARL H. WILLIAMSON AND FLOYD M. WILLIAMSON, OF DETROIT, MICHIGAN.

WINDOW.

Application filed March 6, 1926. Serial No. 92,743.

This invention aims to provide an improved window arrangement wherein each sash is pivotally secured to slides adapted to move up and down in the stile grooves so that the sash may be swung inwards when it and its slides are in any vertical position.

Another object of the invention is to provide a window arrangement wherein the sash cords are so arranged that the sash 10 weights will act as a counterbalance for the sash as it swings inwards as well as supporting the weight of the slides; and at the same time the sash weights balance the weight of the slides and sash in the ordinary manner 15 when the latter is in its normal vertical position.

A further object of the invention is to provide a window arrangement wherein locking means are so arranged as to hold the 20 slides against vertical movement when the sash has been swung inwards to a predetermined extent.

With these and other objects in view which will become apparent as the specification proceeds, the invention is more fully described with the aid of the accompanying drawings, in which:

Figure 1 is a front elevation of a window and frame, and

30 Figure 2 is a section on the line 2—2 of Figure 1.

Figure 3 is a section on the line 3—3 of Figure 2.

Figure 4 is a view showing an angle strip 35 and a sash, the latter swung inwards.

Figures 5, 6, and 7 are sections 5—5, 6—6, and 7—7 respectively of Figure 4.

Figure 8 is a detail showing a catch for holding the sides of the slides.

40 Figure 9 shows a sash cord secured on the inner surface of one of the plates on the side of the sash.

Referring now to the drawings, 1 designates a window frame having the usual stops

45 2. In the stile grooves 2^a between the stops lower and upper slides 3 and 3^a are adapted to move vertically. To these lower and upper slides, and at their lower ends, lower and

50 upper sashes 4 and 4^a are pivotally secured by means which will be more particularly described hereinafter. It will be noted that the upper slides 3^a are wider than the lower slides 3 so as to permit the upper sash 4^a to swing inwards between the lower slides.

55 Now, since the construction of the upper and lower sashes, slides, and their co-relat-

ing parts is similar, we will describe in detail the method of construction of the lower sash, slides and other parts connected therewith.

To the slides 3 angle strips 5 are so secured that one leg 6 of each forms a guide for the plates 7 which extend the full length of the sash and are fastened one on each side of the latter. The plates 7 have their front edges bent over outwardly so that when the sash is in vertical position they will each engage the front edge of one of the legs 6. The other legs 8 of the angle strips extend into the stile grooves 2^a contiguous to the rear surfaces of the slides and have their ends 8^b bent back on themselves to form a receiving groove 8^c for the outwardly projecting portions 9 of the angle-shaped weather strips 10 which are secured to the opposed inner surfaces of the rear stops 2. The rear surfaces of the bent back portions 8^b of the legs 8 then form slides which bear against the face of the rear stops. It will be noted that by this construction the weather strips are utilized also as guides to hold the angle strips and their slides in spaced relation to one another, and so prevent the upper ends of the slides from falling inwards towards one another when the sash is either swung inwards or completely removed. The method of removing the sash will be described hereafter.

Inside the frame 1 are the usual sash weights 12 having ordinary sash cords 13 fastened thereto. The latter pass upward around the usual pulleys 14, down between the stops 2, between the slides 3 and the legs 8 of the angle strips to lower pulleys 15 which are rotatably mounted on the inner surface of the legs 6. Cavities 15^a are provided in the sides of the slides to make room for the pulleys 15. The sash cords pass around these latter pulleys, through the plates 7, and are secured, usually by knots 16, on the 100 inner side of these plates.

On the lower end of each leg 6 a member 17 is fastened. The thickness of these legs and members forms bearing surfaces for pins 18. Intermediately of the length of the latter flats 19 are cut substantially opposite one another, so as to permit this portion of the pins to slide in the slots 20 of the plates 7. In this manner the pins 18 are compelled to turn with the sash and plates. The ends of the pins adjacent to the flats are normally held in position in the

- slots by means of spring catches 21 mounted on the inner sides of the plates 7. The opposite ends of the pins have cam members 22 integral therewith, the ends of these cam members are adapted to force the inbent ends 23 and 23^a of the upset spring sides 24 and 24^a of the members 17 outwards. So that by the rotation of the sash and its plates 7 the pins and their cam members are turned.
- 10 When the sash has passed through a predetermined angle the cam members 22 force the spring sides 24^a and 24 outwards. The former against the inner stops 2, and the latter against the legs 8 which 15 in turn force the legs 9 of the weather strips against the bent over ends 8^b and cause the latter to bind against the rear stops 2.
- When the sashes 4 have been swung inwards 20 the spring catches 21 may be pulled towards one another and the ends of the pins 18 released, so that the latter may be disengaged from the slots 20 and the sash removed from between the slides.
- 25 Towards the upper end of the legs 6 of the angle strips 5 catches 25 are pivotally mounted so as to swing downwards and outwards and engage the upper inner edges of the plates 7.
- 30 When the sash and slides are either closed or open to any desired extent the catches 25 may be moved upwards and the sash released so that it will swing inwards. By pulling the upper part of the sash inwards 35 the latter turns on the pins 18, and the sash cords 13 are pulled outwards as shown in Figure 4, so that the weight of the sash is counterbalanced by the sash weights 12, which latter also continue to counterbalance 40 the slides 3 on account of the cords passing around the pulleys 15. This arrangement of the sash cords also eliminates the possibility of the sash falling suddenly inwards when the catches 25 are released.
- 45 Again the arrangement of the bent front edges of the plates 7 engaging the inner edges of the legs 6 of the angle strips 5, and the members 9 of the weather strips sliding in grooves 8^a eliminates any danger 50 of excessive draught due to the built-up construction of the sash and guides.
- While in the foregoing a preferred embodiment of the invention has been described and shown, it is understood that the construction herein described is susceptible to such modifications as fall within the scope 55 of the appended claims.
- What we claim as our invention and desire to secure by Letters Patent is:
- 60 1. In a window arrangement, the combination of a frame having stops therein, slides adapted to move vertically between said stops, angle strips on the inner and rear surfaces of said slides, a sash pivotally mounted between said slides, said slides hav-
- ing recesses therein, pulleys rotatably mounted on said angle strips and located in said recesses, other pulleys in said frame at its upper end, sash weights in said frame, sash cords having one of their ends attached to said sash, said angle strips having openings therethrough for the passage of said sash cords, said sash cords passing through said openings, around said first named pulleys, up and around said other pulleys, and secured at their other ends to said sash weights. 70
2. In a window arrangement, the combination as described in claim 1, wherein the first named pulleys are so mounted that their axes are substantially at right angles to the width of the sash. 75
3. In a window arrangement, the combination of a frame having stops therein, slides adapted to move vertically between said stops which are materially narrower than the width between said stops, angle strips covering the rear and inner surfaces of said slides, said angle strip rear surfaces having bent over edges, angle weather strips attached to the inner opposed surfaces of the stops behind said slides and having outwardly extending legs spaced from said stops behind which said bent over edges rest, a sash pivotally mounted between said slides, 85 said slides having recesses therein, pulleys rotatably mounted on said angle strips and located in said recesses, other pulleys in said frame at its upper end, sash weights in said frame, sash cords having one of their ends attached to said sash, said angle strips having openings therethrough for the passage of said sash cords, said sash cords passing through said openings, around said first named pulleys, up and around said other pulleys, and secured at their other ends to said sash weights. 90
4. In a window arrangement, the combination of a frame having stops therein, slides adapted to move vertically between said stops, angle strips on the opposed inner surfaces of said slides having outwardly flexed legs contiguous to the rear surfaces of said slides, said legs being bent back on themselves rearwardly to form grooves, angle 100 shaped weather strips on the opposed inner surfaces of the stops behind said slides, said angle shaped weather strips having outwardly projecting portions spaced from the front of the stops to which they are attached, said weather strip outwardly projecting portions taking into said grooves, and a sash pivotally mounted between said slides. 110
5. In a window arrangement, the combination of a frame having stops therein, slides adapted to move between said stops, a sash pivotally mounted between said slides, said slides having recesses therein, strips on said slides across said recesses, pulleys in 115
- 120
- 125
- 130

said recesses rotatably mounted on said strips, other pulleys in said frame at its upper end, sash weights in said frame, sash cords having one of their ends attached to 5 said sash, passing around said first named pulleys, up and around said other pulleys and secured at their other ends to said sash weights.

6. In a window arrangement, the combination of a frame having stops therein, 10 slides adapted to move vertically in stile grooves formed by said stops, angle strips on said slides, plates secured to said angle strips, upturned spring edges on said plates,

15 inbent ends on said upturned spring edges, pins rotatably mounted in said angle strips and said plates, a sash revolvably mounted on said pins and adapted to turn with said pins, and cam members integral with said 20 pins adapted to force said spring edges outwards when said sash has been turned to a predetermined angle.

7. In a window arrangement, the combination as described in claim 6, wherein 25 plates are secured to the sides of the sash, the pins are provided with flats adapted to engage slots extending upwards from the bottom of said plates, and spring catches retain the heads of said pins in said slots.

30 8. In a window arrangement, the combination with a frame having stops therein, slides adapted to move vertically between said stops, angle strips on the opposed inner surfaces of said slides having outwardly 35 flexed legs contiguous to the rear surfaces of said slides, said legs being bent on themselves to form grooves, weather strips attached to the opposed inner surfaces of said stops having outwardly extending legs

40 spaced from the sides of the stops to which they are attached and engaging said

grooves, a sash pivotally mounted between said angle strips, a plate on each side of said sash having its front margins bent over and adapted to engage the front edges of 45 said angle strips when said sash is in alignment with said slides.

9. In a window arrangement, the combination of a frame having stops therein, 50 slides adapted to move vertically between said stops, a sash mounted pivotally between said slides, said slides being materially narrower than the distance between said stops, angle shaped weather strips secured to the opposed inner surfaces of said 55 stops, said weather strips having legs extending outwardly substantially parallel with and spaced from the sides of said stops behind said slides, angle strips attached to said slides having one of their surfaces adjacent to said sash, their other legs adjacent to the back of said slides, and the margins of their other legs bent back on themselves and adapted to slide in the vertical grooves 60 formed between the outward legs on said 65 weather strips and said stops.

10. In a window arrangement, the combination of a frame having stops therein, 70 slides adapted to move vertically in said frame between said stops, strips on the opposed inner surfaces of said slides, pins 75 revolvably mounted in said strips intermediate of their length, a sash detachably mounted on the inner ends of said pins so that said pins and said sash rotate together, and cam members on the outer ends of said pins cooperating with means for holding said sash against vertical movement in said slides when said sash is turned to a predetermined angle.
